UNITED STATES PATENT OFFICE.

WILLIAM N. PELOUZE, OF CHICAGO, ILLINOIS.

DESIGN FOR A BLANK FOR SCALE FRAMES OR BOXES.

SPECIFICATION forming part of Design No. 34,706, dated July 2, 1901.

Application filed November 30, 1900. Serial No. 38,276. Term of patent 14 years.

To all whom it may concern:

Be it known that I, WILLIAM N. PELOUZE, a citizen of the United States, residing at Chicago, in the county of Cook and State of Illinois, have invented and produced a certain new and original Design for a Blank for a Scale Frame or Box, of which the following, in connection with the accompanying drawings, is a full, clear, and exact specification.

Figure 1 is a plan view of a blank for a scale frame or box embodying my design; and Fig. 2 is a transverse section thereof, taken on the line 2-2, Fig. 1.

The leading features of my design consist of a blank for a scale frame or box comprising the portion A and the portion B, projecting from the side thereof. The portion or member A is of substantially oblong form and rounded at each end, as shown at C. The diametrically opposite sides of the member A are substantially parallel and straight save for a number of angular protuberances a' on one of these edges and the member or portion B, extending from the other one. Each end of the member A has a surface ornamen-

tation D, composed of various scrolls and sprays or twigs, and between these ornamentations D is arranged a narrower vertically-elongated ornamentation E, also composed of similar scrolls and twigs. The member A is 30 arranged opposite one end of the surface ornamentation E, and it is substantially oblong in general outline, with its longest diameter extending at right angles to the longest diameter of the member A. The sides or longer 35 edges of the member B are scalloped, as shown at b, and above the center is located a pair of perforations $b' b^2$ of different sizes, while surrounding these is an oblong rib or welt F.

Having thus described my invention, what I claim as new therein, and desire to secure by Letters Patent, is—

The design for a blank for a scale frame or box substantially as herein shown and described.

WM. N. PELOUZE.
